UNITED STATES PATENT OFFICE.

HERMANN ROMÜNDER, OF MILWAUKEE, WISCONSIN.

TUBE-MAKING MACHINE OR PRESS.

SPECIFICATION forming part of Letters Patent No. 781,742, dated February 7, 1905.

Application filed June 4, 1904. Serial No. 211,216.

To all whom it may concern:

Be it known that I, HERMANN ROMÜNDER, a citizen of the United States, and a resident of Milwaukee, county of Milwaukee, State of Wisconsin, have invented certain new and useful Improvements in Tube-Making Machines or Presses, of which the following is a specification.

My invention relates more particularly to machines or apparatus in which under simultaneous influence of heat and pressure sheets or plates of material, generally in the form of two or more ply wood-veneer plates of any desired thickness and curvature, may be pressed and the overlapped portions thereof forced into intimate union with each other to form practically seamless hollow tubes which may be used for a great variety of purposes.

The objects of my invention are to provide an efficient, economical, and rapid machine of simple construction and comparatively low cost by the use of which, first, the overlapped portions of substantially bent or curved sheets or plates of material, as wood-veneer plates consisting each of a number of layers of wood or wood veneer glued together under heat and pressure with reversed grain by means of any suitable waterproof cementing composition—such, for example, as a compound of glue and potash—may be united and glued together under the influence of heat and pressure and by means of any suitable waterproof cementing composition applied to the overlapping parts, and, second, the said plates of material pressed to assume and retain a curved form with a curvature of greater or less pitch, as desired, resulting in the formation of hollow tubes which are practically seamless and combine simplicity and cheapness of construction with greatest strength and durability and which may be used as pipes, conduits, or cylinders or for the mantles of barrels, drums, and other like packages and for various other purposes.

To these ends my invention consists in the features of construction and devices hereinafter described, and more particularly set forth in the appended claims.

The preferred form of the invention is illustrated in the accompanying drawings, form-

ing part of this specification, wherein like characters of reference indicate like parts throughout the several views.

The drawings illustrate more particularly my improved machine as adapted for the manufacture of barrel-mantles; but I do not, of course, limit myself to the production of this class of articles only, as the same apparatus may also be applied for the purpose of producing tubes for a great number of other purposes.

Figure 1 is a front elevation of a machine embodying my invention, partly in vertical section, showing a tube compressed between the extended inner block or core and the several press-plates. Fig. 2 is a vertical sectional view of a portion of the apparatus, showing the tube loosely on the collapsed core and the outer press-plates in reversed position, (when the press is open.) Fig. 3 is a vertical section on line *xx* of Fig. 1. Fig. 4 is a plan view showing the framework, the hydraulic presses, and the wedge.

A is the framework, consisting chiefly of a suitable casing with a base, side and rear portions, and top plate forming a rigid structure which the movable parts are mounted on and connected to in suitable manner, preferably as hereinafter shown and described.

B, *C*, and *D* are sections or sectors which together form the expandable and collapsible inner block or core on which the material to be compressed is placed in any suitable manner and which when expanded has an outer circumference equal to the inner circumference of the finished tube. The sector *B* has an extension *E* at its rear portion, by means of which it is suitably secured to the rear portion of frame *A*, and thus becomes rigidly connected thereto. The sectors *C* and *D* are slidably connected with each other and with sector *B* and movably held in relative position to each other by suitable means, as pins or guide-rods *b b*. *F* is a wedge horizontally movable between the said sectors *B*, *C*, and *D*, supported by the framework *A* and sector *B*, and arranged to reciprocate horizontally by suitable means, as the cog-wheel *c*, suitably mounted on the frame *A* and meshing with the rack or gear-rail *d*, provided on the rear portion of

wedge F, the said cog-wheel being actuated by suitable means, as pulleys M, from a source of power. (Not shown.) The surface of wedge F facing the core-section B is preferably straight or flat, corresponding to the meeting surface of sector B, and the surface of wedge F facing the core-sections C and D is tapering, corresponding to the tapering meeting surfaces of sectors C and D. By these means the sectors C and D may be raised and lowered and the core expanded and collapsed as the wedge F is moved forward and back, and the sectors B, C, and D and the wedge F may be provided with suitable longitudinally-extending tongues and grooves e or other means to assure a uniform expansion of the core and a true alinement of the said movable parts.

G and H are pistons each adapted to be moved horizontally through the action of fluid-pressure introduced into the cylinder-casings I I, both cylinders being fed by one press-fluid supply or feed pipe f, whereby both these presses operate simultaneously. The pistons G and H may be arranged to slide horizontally between the base and the top plate of the framework A in any suitable manner, as shown in Figs. 1 and 2, so as to prevent binding.

K is a vertically-reciprocating piston movable in cylinder-casing L, which is fed by a separate supply-pipe g, whereby this press may be operated independently of the horizontal hydraulic presses.

The pistons G, H, and K, as well as the top plate of the frame A, are provided with suitable press-plates M, N, O, and P, integral therewith or detachably connected thereto by suitable means, as bolts or screws, each of the said press-plates having a concave surface conforming to the convex surface of the portion of the core facing each of the said press-plates. Each of these press-plates M, N, O, and P and the sectors B, C, and D is preferably hollow and provided with flues or openings R R, arranged to be heated by any suitable means, as electricity, gas, steam, or other means. In the drawings the press-plates and sectors are shown to be heated by means of steam entering through inlets h h and discharging through outlets i i, whereby the pressing-surfaces may be heated to the desired degree to act upon the material a to be pressed and upon the waterproof cementing composition applied to the overlapping portions of the material to be joined under heat and pressure. These press-plates M, N, O, and P and the said core-sections B, C, and D may all be heated to a uniform temperature sufficient to heat the material and permit the bending thereof to the desired form and the joining of the overlapping parts, or the core-sections may be heated to a considerably higher temperature than the press-plates, so much so that the surface of the material a exposed to the said core-sections will become charred to a greater

or less degree, as desired. When thus charred on the inner surface, the tubes formed of this material may be utilized for mantles of liquor or wine barrels and packages or other purposes requiring charred surfaces. This material a consists, preferably, of a number of waterproof wood-veneer plates or other suitable material with overlapped portions k k, which are designed to be glued and pressed together between the pressing-surfaces of the pistons and the core-sections under sufficient heat and pressure, continued thereunder for a sufficient time to enable them to set and become virtually integral with each other, the waterproof cementing composition with which the overlapped portions have been coated binding them together to one practically homogeneous and seamless piece of material. Any suitable waterproof cementing composition may be used for this purpose—such, for example, as a compound of glue and potash.

Suitable means, as counterweights S S, resting when released on brackets l l, mounted on or detachably connected to the framework A, may be provided to return the pistons of the horizontal presses as soon as the hydraulic pressure is released.

When the material a is intended to form a tube to be used as a barrel-mantle, suitable hoops r r and bung-plates s s may be simultaneously connected and pressed to said material, and in that case I provide suitable recesses n n in the pressing-surfaces of plates M, N, O, and P to accommodate the hoops r r and bung-plates s s, and in practice I preferably place the material so onto the core that the hoops and bung-plate are cemented to and cover the overlapped portions of the mantle and are pressed together therewith by the vertical hydraulic press.

The operation of my improved machine is as follows: The machine standing idle, the wedge F being in its extreme outer position, as shown in dotted lines in Fig. 3, the core being in its collapsed position, and the horizontal and vertical presses being open, as shown in Fig. 2, the material a required to form the tube is placed in position over the core, the overlapping portions of the material having previously been coated with any suitable cementing composition and the hoops r r and bung-plate s having been tacked on or otherwise placed and held in position on the material in case the tube is to be used as a barrel-mantle. The wedge F is then moved forward by means of the cog-wheel c until it reaches its inner position and the core is entirely expanded, when its circumference is equal to the inner circumference of the material and the core presses the material against the press-plate M of the top plate of frame A. The fluid-pressure is then turned on by operating the supply-pipe f, starting the horizontal hydraulic presses simultaneously, the pistons of which compress the portions of the material

covered by the curved surfaces of the press-
plates N and O against the inner core. Then
the vertical press is started by operating feed
or supply pipe γ , when piston K, with its
5 press-plate P, compresses the bung-plate s and
the hoops r r and the overlapped portions k k
of the material against the core and forces
them into intimate union. The apparatus then
10 stops and is allowed to stand, exerting this
fixed pressure until the overlapped portions
k k of the material a have assumed permanent
union and the material becomes practically
one continuous homogenous and seamless tube
15 impervious to moisture and atmospheric in-
fluences and the hoops r r and the bung-plate
s have also been glued to or otherwise united
with the tube, it being understood that the
press-plates M, N, O, and P and the core-sec-
tions B, C, and D are sufficiently heated dur-
20 ing the pressing operation by means of steam
circulating through the flues or chests R R or
otherwise to bring about the desired result un-
der simultaneous heat and pressure, and the
tube may be charred to any desired degree on
25 its inner or outer surface, or both, by means
of increasing the temperature of the press-
plates M, N, O, and P or the core-sections
B, C, and D, or both, sufficiently to accom-
plish this purpose. The vertical hydraulic
30 press is then opened, the piston K sliding
downward of its own weight as soon as the
fluid-pressure through pipe γ is released.
Then the horizontal hydraulic presses are
35 opened, the water-supply through pipe f be-
ing shut off, the pistons G and H returning by
means of the counterweights S S or other
means provided for this purpose. Then the
wedge F moves back to its previous outer po-
40 sition by the reverse action of cog-wheel c,
when the core collapses, and the finished tube
may then be taken from the apparatus by lift-
ing it from the collapsed core, the said mate-
rial a retaining the exact shape it has assumed
45 between the press-plates and the core-sections
under heat and pressure and the overlapped
portions of the material having practically be-
come one homogeneous piece of material, the
said material thus forming a practically con-
tinuous and seamless tube of desired shape.
50 By inserting and suitably securing to the pi-
stons and the frame A press-plates and core-
sections having surfaces with a curvature of
greater or less pitch the same machine may
55 be used for forming and pressing tubes with
larger or smaller diameter and of cylindrical,
oval, or other desired shape.

By means of this machine I am able to form
two or more ply wood-veneer plates or other
suitable material and unite the overlapped
60 portions thereof, so as to produce tubes suit-
able for pipes, conduits, barrel-mantles, or
other structures of any desired shape and
size in which curvature of greater or less
pitch is desired and to char one or both sur-
65 faces of said tubes to a greater or less degree,

as may be required, when they may be used
for any of the purposes above stated necessi-
tating charred surfaces.

This invention is susceptible of many modi-
fications, and the details of operation and con-
struction of this machine may be varied from
the above description without changing the
principle of my invention so long as sheets or
70 plates of suitable material may be bent and
pressed therein to assume and retain a curved
75 form of greater or less pitch and the over-
lapped portions joined and forced into intimate
union with each other, so that the material
will form practically continuous and seamless
80 hollow tubes. I do not, therefore, limit this
specification and the claims to the precise
forms of the invention illustrated in the draw-
ings and hereinbefore described.

I claim—

1. An improved tube-making press, com-
posed of a suitable frame, an expansible and
collapsible inner block or core, consisting of
a number of sectors, separably held together,
a vertically-reciprocating piston and a num-
ber of horizontally-reciprocating pistons, all 85
suitably mounted on and supported by said
frame, a number of press-plates suitably se-
cured to said sectors and said pistons, means
whereby the said core may be expanded and
collapsed and means whereby the said press-
90 plates may be heated.

2. An improved tube-making press, com-
posed of a suitable frame, forming a rigid
structure, an expansible and collapsible inner
block or core, consisting of a number of sec-
tors, one of said sectors being suitably con-
nected to said frame and the other sectors be-
ing slidably connected to each other and to
said stationary sector, and movably held in
relative position to each other by suitable 100
means, a vertically-reciprocating piston and
a number of horizontally-reciprocating pis-
tons, movable within and supported by said
frame, a number of press-plates suitably se-
cured to said sectors and said pistons, means 105
whereby the said core may be expanded and
collapsed and means whereby the said press-
plates may be heated.

3. An improved tube-making press, com-
posed of a suitable frame, an inner block or
core, consisting of a number of sectors sepa-
rably held in position, and arranged to be ex-
panded and collapsed, a vertically-reciprocat-
ing piston and a number of horizontally-re-
ciprocating pistons, all suitably mounted in 115
said frame, press-plates suitably secured to
said sectors and said pistons, means whereby
the said core may be expanded and collapsed,
means whereby the said horizontally-recipro-
cating pistons and press-plates secured thereto 120
and the said vertically-reciprocating piston
and press-plate secured thereto may be forced
and held against the said core when expand-
ed, and the interposed material pressed and
joined between the press-plates of the core 125

and the press-plates of the pistons and means whereby the said press-plates may be heated.

4. An improved tube-making press composed of a suitable frame, a vertically-reciprocating press-plate and horizontally-reciprocating press-plates, movable within and supported by said frame, an expansible and collapsible core consisting of a number of sectors, one of said sectors being rigidly connected to said frame with its extended rear portion, and the other sectors being suitably held in relative position to each other and to said stationary sector, and arranged to be separated and expanded or collapsed, said press-plates and core-sections being adapted to receive between them the material to be pressed, means whereby the said core may be expanded and collapsed, means whereby the said press-plates may be operated to compress the material against the expanded core, and means whereby the said material may be heated during compression.

5. An improved press composed of a suitable frame, forming a rigid structure, a vertically-reciprocating press-plate and horizontally-reciprocating press-plates, movable within and supported by said frame, a stationary core-section rigidly connected to said frame in suitable manner, and a number of movable core-sections suitably held in relative position to each other and to said stationary core-section and supported by said stationary core-section and arranged to be separated; the said core-sections forming together an expansible and collapsible core; said press-plates and said core-sections being arranged to be heated by steam or other means, and adapted to receive between them the material to be pressed; means for expanding and collapsing the said core, to allow the placing in position of the material to be pressed and joined under simultaneous heat and pressure, and the removal of the material after compression, and means whereby the said press-plates may be operated and the material compressed and joined to form a practically seamless homogeneous tube.

6. A tube-press, composed of a suitable frame, a vertically-reciprocating piston and a number of horizontally-reciprocating pistons, suitably mounted in and supported by said frame, means whereby the horizontally-reciprocating pistons may be operated simultaneously and means whereby the vertically-reciprocating piston may be operated independently of said horizontally-reciprocating pistons, press-plates suitably secured to said pistons, a stationary core-section rigidly connected to said frame in suitable manner, and a number of movable core-sections, supported by said stationary core-section and held slidably in relative position to each other and to the said stationary core-section, the said

core-sections forming together an expansible and collapsible core, means whereby the said core may be expanded and collapsed and means whereby the said press-plates and the said core-sections may be heated.

7. An improved tube-press, composed of an expansible and collapsible core, a vertical hydraulic press and a number of horizontal hydraulic presses, set in a suitable frame; the said core consisting of a stationary section, rigidly connected to said frame, and a number of movable sections, supported by said stationary section and slidably held in position with each other and the stationary section and arranged to be separated from each other and from the stationary section, press-plates suitably secured to the pistons of the hydraulic presses, means whereby the said core may be expanded and collapsed, means whereby the press-plates and core-sections may be heated and means whereby the said press-plates and core-sections may be forced and held together to press and join the material placed in position over said core.

8. In an improved tube-press a number of horizontally-reciprocating pistons, a vertically-reciprocating piston and a collapsible and expansible core, consisting of a number of sections, all suitably mounted in a rigid frame structure, press-plates suitably secured to the said pistons and the said core-sections, means whereby the said core may be alternately expanded and collapsed, means whereby the said pistons may be operated as required and means whereby the said press-plates and the interposed material may be heated, the press gluing the overlapped portions of the material together by means of a waterproof cementing composition under heat and pressure and producing a practically homogeneous seamless tube, impervious to moisture and atmospheric influences.

9. An improved tube-press, composed of a suitable frame, a number of core-sections forming a collapsible and expansible core, suitably mounted in said frame, and a number of press-plates supported by said frame, one of said press-plates being movable vertically and the other press-plates being movable horizontally, means whereby the said press-plates may be operated as required, means whereby the core may be expanded for the compression of the material placed in position over the said core, and collapsed to allow the placing in position of the material to be pressed and joined and the removal of the material after compression, and means whereby the said press-plates and core-sections may be heated.
